Primary Examiner — John R Yeh

(57) **CLAIM**

The ornamental design for a storage furniture, as shown and described.

DESCRIPTION

FIG. 1 is a front and top perspective view of a storage furniture, showing my new design;

FIG. 2 is a rear and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion, labeled '9' of FIG. 1;

FIG. 10 is an enlarged view of the portion, labeled '10' of FIG. 1; and,

FIG. 11 is an enlarged view of the portion, labeled '11' of FIG. 1.

The broken lines depict portions of the storage furniture that form no part of the claimed design.

1 Claim, 11 Drawing Sheets
